UNITED STATES PATENT OFFICE

GEORGE F. LARTZ, OF MORTON GROVE, ILLINOIS

MOUNTING DEVICE FOR PICTURES

Application filed March 30, 1928. Serial No. 265,914.

This invention relates to improvements in mounting devices for cards, photographs, pictures and the like, and one of the objects of the invention is to provide an improved 5 mounting device of this character formed from a single piece of material, preferably ready gummed, so shaped that in folding the same it becomes a pocket adapted to be secured to any surface, and into which pocket 10 the corner of a card or picture is adapted to be inserted, and by means of which the card or picture will be lightly but firmly held in position.

A further object is to provide an improved 15 mounting pocket of this character, portions of which may be embossed as desired for ornamentation and which may as well be printed in colors or otherwise artistically decorated to present a pleasing appearance.

20 To the attainment of these ends and the accomplishment of other new and useful objects as will appear, the invention consists in the features of novelty in substantially the construction, combination and arrangement 25 of the several parts hereinafter more fully described and claimed and shown in the accompanying drawing illustrating this invention, and in which

Figure 1 is a perspective view of a mounting device of this character constructed in 30 accordance with the principles of this invention, showing the same applied to a mounting surface and indicating in dotted lines one corner of a card or picture inserted therein.

35 Figure 2 is a top plan view of the blank from which the device shown in Figure 1 is formed.

Figure 3 is a view of the blank partially 40 folded.

Figure 4 is a top plan view of the blank completely folded.

Figure 5 is a top plan view of a blank for 45 another form of pocket.

Figure 6 is a view showing the blank of 50 Figure 5 partially folded.

Figure 7 is a top plan view of the completely folded blank.

55 Referring more particularly to the drawing and to the form of the invention shown in Figures 1 to 4, the blank consists essentially

of a body portion 10 having portions 11-12 arranged at substantially right angles to each other, the outer corner of the blank formed by a prolongation of the outer edges of the portions 11 and 12 being cut away or shaped as at 13 to provide any configuration for the top of one of the walls of the pocket. The blank thus formed is preferably gummed on one face, which in Figure 2 is the upper surface and in Figure 3 the under surface, 60 as indicated by the reference numeral 14 in Figure 3.

The portions 11-12 (see Figure 2) are respectively folded back upon the body portion 10 along the lines 15 and 16 as shown more 65 clearly in Figure 3, in the inverted form and then the portions 11-12 are bent back upon themselves respectively along the lines 17-18, to form portions 19 and 20 that are adapted to be secured to a mounting surface 70 21. When thus folded the portion 10 will constitute the front wall of the pocket while the portions formed respectively between the lines or edges 15-17 and 16-18 constitute 75 the rear wall of the pocket. This rear wall extends preferably for a considerable distance beyond the top edge 13 of the front wall of the pocket and the edges 17 and 18 terminate short of each other or in close proximity thereto as shown in Figure 4.

80 By providing a rear wall to the pocket which is divided it will be manifest that the rear wall may be slightly separated so as to compensate varying sizes of card corners to be inserted into the pocket.

Obviously the front face of the front wall of the pocket may be embossed or suitably ornamented.

85 In the form of the invention shown in Figure 5, the body 22 is folded along the lines 23-24 to produce a front wall 25 for the pocket, the upper edge of this wall being suitably shaped as at 26. The portions 27 of the body beyond the folded edges 23-24 constitute the back wall of the pocket and the 90 extremities 28 of the portions 27 are folded along the lines 29 back upon the portions 27 so that the gummed surfaces of the portions 28 will be presented to the mounting surface 21 to be secured thereto. The edges 30 of 95

the portions 27 will be disposed in close proximity to each other to form a divided rear wall for the pocket and the portions 27 may project for any desired distance beyond the 5 top edge 26 of the front wall 25.

While the preferred forms of the invention have been herein shown and described, it is to be understood that various changes may be made in the details of construction and in 10 the combination and arrangement of the several parts within the scope of the claims, without departing from the spirit of this invention.

What is claimed as new is:—

15 1. A mounting device of the character described comprising a body formed from a single piece of material comparatively long with relation to its width and having one gummed face, portions of the body on opposite 20 site sides of the longitudinal center being folded towards each other and back upon the same face of the body to provide a pocket, the bottom wall of the pocket extending for a considerable distance beyond the inner edge 25 of the opposite side of the pocket, the said extended portions being folded back upon themselves and away from each other to form flaps presenting their gummed faces to a mounting surface and with the edges of the 30 blank formed by the last recited fold in close proximity to each other.

2. A mounting device of the character described comprising a body formed from a single piece of material comparatively long 35 with relation to its width and having one gummed face, the ends of the material being folded back upon the same face of the body to bring the gummed portions of said face in proximity and to provide a pocket, the bottom 40 wall of the pocket extending for a considerable distance beyond the inner edge of the opposite wall of the pocket, the adjacent edges of the said folded back portions being disposed in close proximity to and being substantially parallel with each other and intersecting the pocket transversely of the body 45 portion, the extremities of said folded portions being bent back upon themselves and against the same face of the pocket to present the gummed surfaces of the said extremities to a mounting surface.

3. A mounting device of the character described comprising a body formed from a single piece of material comparatively long 55 with relation to its width, portions of the material on opposite sides of a longitudinal central point being bent back upon the body transversely thereof and towards said central point to form a pocket the bottom wall of 60 which extends beyond the inner edge of the front wall, portions of the extended wall being bent back upon themselves and against the same face of the pocket wall to provide anchoring flaps disposed behind the rear wall 65 of the pocket.

4. A mounting device of the character described comprising a body formed from a single piece of material comparatively long with relation to its width, portions of the material on opposite sides of a longitudinal central point being bent back upon the same surface of the body and towards said central point to form a pocket, the bottom wall of which extends beyond the inner edge of the front wall, the proximate edges of the portions forming the bottom wall of the pocket being disposed in proximity to each other to provide a divided wall intermediate the ends of the pocket, portions of the extended wall being bent back upon themselves and against the same face of the pocket wall to provide anchoring flaps disposed behind the bottom wall of the pocket.

5. A mounting device of the character described comprising a body formed from a single piece of material comparatively long with relation to its width, portions of the body on opposite sides of the longitudinal center being folded towards each other and back upon the same surface of the body to provide a pocket, the bottom wall of the pocket extending for a considerable distance beyond the inner edge of the opposite wall of the pocket, the said extended portions being folded back upon themselves and against the same face of the pocket wall and away from each other to form flaps presenting their gummed faces to a mounting surface.

In testimony whereof I have signed my name to this specification, on this 24th day of March, A. D. 1928.

GEORGE F. LARTZ.
